J. H. WEISBROD,
END CONSTRUCTION FOR BOX CARS.
APPLICATION FILED MAY 28, 1915.

1,209,088.

Patented Dec. 19, 1916.

UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

END CONSTRUCTION FOR BOX-CARS.

1,209,088.

Specification of Letters Patent.

Patented Dec. 19, 1916.

Application filed May 28, 1915. Serial No. 30,944.

To all whom it may concern:

Be it known that I, JACOB H. WEISBROD, a citizen of the United States, residing at the city of St. Louis, State of Missouri, have 5 invented a certain new and useful Improvement in End Construction for Box-Cars, of which the following is a full, clear, and exact description, such as will enable others skilled in the art to which it appertains to 10 make and use the same, reference being had to the accompanying drawings, forming part of this specification.

This invention relates broadly to railway car construction, and specifically to certain 15 features of body construction.

In the use of sheet metal ends in box cars, the most frequent failures have occurred in the means of attachment employed for affixing the end sheet to the car super- 20 structure. The cause of such failures is most commonly the inertia thrusts of lading in the car, which are occasioned by sudden stopping or starting of the car.

The present invention is designed to 25 provide an improved form of body and end construction, the purpose of which is to afford a means of attachment for the car end which will have the maximum strength and thrust-resisting stability.

20 A further purpose of the invention is to provide a car end construction in which not only the end wall itself, but the end portions of the side walls adjacent thereto, are formed of sheet metal, the form of construction of such parts being such as to 25 adapt them for attachment to wooden car bodies as repair parts.

A further object of the invention is to 30 provide a construction employing metallic end and side sheets formed and connected to provide a support for the side plates or upper longitudinal framing members of the car framing at their extremities.

Other and further objects of my invention 35 will be obvious or pointed out herein-after.

In the accompanying drawings, I have 40 illustrated one embodiment of my invention, Figure 1 representing a vertical sectional view, showing an interior elevation of a side portion; Fig. 2, a sectional view taken approximately on line 2—2 of Fig. 1, showing a part interior elevation of the end sheets, and showing the disposal of certain framing 45 and lining members in association with the

parts illustrated in Fig. 1; Fig. 3, a detail taken on line 3—3 of Fig. 1, and showing in addition the corner post and lining; Fig. 4, a detail showing a top view of the corner; Fig. 5, a horizontal section taken at the 60 transom post, substantially at line 5—5 of Fig. 1, but showing additional wall portions not shown in Fig. 1.

From said drawings, it will be understood that 1 represents one section of a sheet 65 metal car end, and 2 another section. These sections are suitably connected together to form the end wall, and are connected to framing members at the top and bottom of the end, 4 representing the end sill, or the 70 lower one of such framing members. The top and bottom margins of the sections are deflected rearwardly to form attaching flanges 5, and the side margins are turned rearwardly to form the side attaching 75 flanges 6. At the ends of the sides of the car, I dispose the sheets 7. These sheets extend from top to bottom of the car side wall, forming in fact the outer side wall at the end of the car, and extend backwardly 80 from the end sheets 1 and 2 as far as desired, that illustrated being formed to extend back to the transom post P, as shown in Fig. 5, and being flanged inwardly at 8 and rearwardly to provide the flange 9 which 85 is adapted to extend behind the transom post. These sheets are stiffened horizontally by angles 10, and vertically by an angle 11 extending from their outer upper to lower inner corners, and having its end adjacent the 90 outer upper corner turned horizontally to provide a step 12. The front edges of sheets 7 are flanged over the lateral edges of the end sheets 1 and 2 as illustrated in Fig. 3, the end sheets and side sheets being secured together to form a corner in which a wooden corner post 14 may be disposed, and bolted to the adjacent sheets by bolts 15, said corner post forming an attaching place for the inner wall sheathing 16. Along the upper 100 edge of each sheet 7 is disposed a Z-shaped member 17, the same being adapted to act as a pocket member for the reception of the side plate. This pocket member is attached at its forward edge to the upper attaching 105 flange 5 at the top of the end sheets, as is best illustrated in Fig. 4. The upper flange of this Z-shaped member is widest at its edge where attached to the end sheet, and tapers back from said end to its rear ter- 110

minus which is adjacent the flange 8. Near its forward end the lower horizontal flange of said Z-shaped member rests upon the step 12. The side sills 18 are in the form 5 of Z bars, secured at their ends to the end sills by angle members, and disposed with their upper horizontal flanges overlapping the lower flange 5 beneath the wood flooring. The vertical web of the side sill is spaced 10 apart from the side sheet, and the side sill is connected to the side sheet by an angle 19, which provides a pocket below the floor level and intermediate the vertical web of the side sill and the outer side wall formed by sheet 15 7. This angle 19 terminates adjacent flange 8.

When the construction is assembled on the car, the pocket formed by side sill 18 and angle 19 receives a floor nailing strip 20 20 which is bolted to the metal members and which forms the attaching member for the floor boards. The end of the side plate S is received in the pocket formed between the vertical web of pocket member 17 and side 25 sheet 7, the plate resting upon the lower horizontal flange of member 17 and the end of the side plate being abutted against a filler block 21 positioned in the end of the pocket and bolted to the vertical web of 30 pocket member 17, the side sheets 7, and the flange 6. To accommodate the side plate, the upper extremities of the flanges 8 and 9 are cut out as shown in Fig. 1. The side plate is bolted to the vertical web of pocket 35 member 17 and to side sheet 7, and a gusset plate 22 is applied on the exterior of the car wall over the cut-out corner of side sheet 7, said gusset plate being bolted to the transom post and to the side plate, side sheet 7, 40 and pocket member 17. In case inside sheathing is desired, a nailing strip 24 may be secured to the angle 10 and the inner wall sheathing 16 secured thereto and to the nailing strip 20. A purlin 26 and a fascia 27 45 may be secured to the flange 5 and the upper margin of the side sheet as a support for roof plates 28.

It will be observed that this construction is particularly adapted to be applied to cars 50 in which the ends and portions of the sides adjacent the ends have been damaged. While thus adapted as a repair construction, at the same time, it will be observed that it may be advantageously employed as an 55 original construction, as it forms a particularly strong end construction, the side sheets 7 being secured throughout their length to the upper and lower longitudinal framing

members, and said side sheets forming a continuous connection between the end 60 sheets and the transom post.

In addition, it will be observed that the structure does not require a corner post, as it is self-sustaining and a suitable corner construction is secured by the overlapping 65 attachment of the side sheets and end sheets.

It is obvious that end sheets corrugated, ribbed, or reinforced in any suitable form to give them strength, may be employed in this construction, and that the structure is 70 susceptible of various changes and modifications without departing from the spirit and scope of the invention. Hence, it is not my intention that the following claims be construed as limited to the specific form illustrated and described.

What I claim is:

1. A car end construction comprising end wall sheets, vertically disposed side wall sheets secured at one edge to the end wall 80 sheets and at the other edge to vertical car body frame members, a pocket member secured to the upper portions of adjacent end and side wall sheets and forming a pocket for the reception of a longitudinal side 85 framing member.

2. In a car construction, the combination of end wall sheets, side wall sheets vertically disposed and connected at their forward edges to the lateral margins of the end wall 90 sheets to form corners, said side wall sheets being secured at their rearward vertical margins to vertical car body frame members, a pocket member secured to the upper portion of an end wall sheet, said pocket member 95 and the upper portion of the side wall sheet being secured to a longitudinal car body frame member.

3. In a car construction, the combination of end wall and side wall sheets secured together on vertical edges to form a corner, said side wall sheet being secured at its other vertical edge to a vertical car body frame member, a vertical stiffening member applied to said side wall sheet, the upper portion of said side wall sheet being secured to a longitudinal car frame member, and a pocket member secured to the end wall sheet 100 and to such longitudinal frame member.

In testimony whereof I hereunto affix my 110 signature in the presence of two witnesses, this 15th day of May, 1915.

JACOB H. WEISBROD.
